UNITED STATES PATENT OFFICE.

JOHN PEYER, OF BROOKLYN, NEW YORK.

TOOL HANDLE.

Application filed January 19, 1923. Serial No. 613,624.

To all whom it may concern:

Be it known that I, JOHN PEYER, a citizen of the United States, and a resident of the city of New York, borough of Brooklyn, in the county of Kings and State of New York, have invented certain new and useful Improvements in a Tool Handle, of which the following is a specification.

Among the principal objects which the present invention has in view are: To quickly and readily alter the operation of the tool as a ratchet tool operating successively clockwise and contrawise, and a direct operating tool operating as controlled by the operator; to simplify the shifting mechanism by which the change in the operation of the tool is effected; and to simplify and cheapen the operation and construction of the handle.

20

Drawings.

Figure 1 is a side view of a tool handle constructed and arranged in accordance with the present invention.

25 Figure 2 is a lengthwise section on the line 2-2 in Fig. 1.

Figure 3 is a cross section, the section being taken as on the line 3-3 in Fig. 2.

30 Figure 4 is a cross section taken as on the line 4-4 in Fig. 2.

Figure 5 is a lengthwise section of the tool handle and tool, the ratchet member being shown as engaged with the chuck of the tool.

35 Figure 6 is a cross section of the handle, the section being taken as on the line 3-3 in Fig. 2, showing the ratchet engaging member in operative relation to the shank of the tool chuck.

40

Description.

As seen in the drawings the body 11 of the handle is preferably constructed of metal having a socket to receive the reduced end 12 of the wooden handle 13. The body 11 is elevated at one side to provide a mount 14 in which the latch 15 is reciprocatively mounted, a bore being driven lengthwise through the mount 14 to accommodate the said latch and the spring 16 thereof. The forward end of the latch engages in service a mutilated wheel 17.

45 The wheel 17 is pivotally mounted in the body 11 by means of a shaft 18. The shaft 18 is eccentrically disposed with relation to the wheel 17, a flatted portion 19 on the

wheel 17 corresponding with a flatted portion 20 on the chuck head 21.

The chuck head 21 is provided with a flange 22 adapted to engage for housing 60 purposes a screw ferrule 23 and to rest with in the same.

The inner end of the chuck head has a serrated portion 24, the serrations extending lengthwise thereof. These serrations 65 are engaged by serrations on the wheel 17 in accordance with the direction in which the wheel 17 is rotated. The serrations on the wheel 17 and the portion 24 of the chuck while fine are sufficient to prevent slippage 70 in their engagement. The eccentricity of the wheel 17 causes the same to jam or bite when the handle is rotated in the direction to which the major axis of the wheel inclines. To lock the wheel 17 in working 75 position it is provided with a series of shallow sockets 25 which when engaged by the finder 26 hold the said wheels as placed.

It will be noted by reference to Fig. 3 of the drawings that the finder 26 is shown as 80 engaged with the center socket, in which position the wheel 17 is moved out of engagement with the portion 24 to a position above the flatted portion 20 of the chuck head 21. The flatted portions 19 and 20 of 85 the wheel and chuck respectively being thus engaged, the chuck is prevented from rotating independently of the handle.

The finder 26 yields slightly from its socket to permit a free backward or ratchet 90 action of the wheel 17, the tension of the spring 16 being sufficient however, to restore the wheel to set position on forward movement in rotation of the handle.

The wheel 17 is moved to engage the flatted portion 20 of the chuck 21 by the finder 26 and the spring 16 which thrusts the said finder forward.

By reference to Fig. 6 it will be seen that the wheel 17 is swung to a position where 100 the center socket 25 has been released and one of the side sockets have been engaged by the finder 26.

It will be understood that the wheel 17 is shifted lengthwise of the shaft 18 by hand. 105 The chuck head 21 is held in service relation to the body 11 by the ferrule 23. The chuck has an extension 28 in which a cylindrical socket 29 is bored. A pin 30 is driven through the extension 28 and through the 110 socket 29. The side of the pin 30 forms a rest for a flattened portion 31 of a working

tool 32. The end of the working tool 32 as seen in Fig. 1 of the drawings extends when in service into the opening 33 formed by boring a straight hole to the chuck.

5 The body 11 is held in service on the handle 13 by means of a headed pin 34.

From the foregoing it will be seen that the tool 32 may be rapidly and easily installed or liberated from service. In accordance 10 with the disposition of the wheel 17, the tool will be worked ratchet-wise in either rotary direction or in conformity with the movement of the handle 13 if disposed in position where the flaps 19 and 20 engage. It is obvious 15 that these dispositions of the wheel 17 can be easily and readily made.

Claims.

1. A tool handle comprising a grip portion, a chuck head rotatively connected thereto, a member pivotally and eccentrically mounted on said grip portion to engage said chuck head for ratchet action with the grip portion, and slidably mounted on said grip portion to engage said chuck head for positive direct action with said grip portion.

2. A tool handle comprising a grip portion, a chuck head rotatively connected thereto, a lateral extension on said grip portion, a member slidably disposed in said extension and adapted to engage said chuck head for positive actuation of said chuck head with said grip portion, said member being eccentrically and pivotally mounted in said extension for ratchet action with said chuck head on proper positioning of the member.

3. A tool handle having an operating handle, and a chuck head rotatively connected thereto, said chuck head having a cylindrical roughened engaging portion and a flattened portion; a mutilated rocking member having a flattened portion and an engaging periphery corresponding with the surface 40 of the engaging portion of said chuck head; and means for slidably mounting said member for disposing the same in operative relation to said roughened portion and to the flattened portion of said chuck head.

50 4. A tool handle having an operating handle, and a chuck head rotatively connected thereto, said chuck head having a cylindrical roughened engaging portion and a flattened portion; a mutilated rocking mem-

ber having a flattened portion and an engaging periphery corresponding with the

surface of the engaging portion of said chuck head; and means for slidably mounting said member for disposing the same in operative relation to said roughened portion and to the flattened portion of said chuck head, said means embodying a stud bearing slidably supporting said member.

5. A tool handle having a grip portion; a chuck head adapted to receive a working tool, said chuck head having a flattened portion and a cylindrical engaging roughened portion, said roughened portion and flat portion being adjacently disposed; a mutilated wheel eccentrically and slidably mounted on said grip portion adjacent said flattened and roughened chuck head portion, said wheel having a flattened portion and roughened periphery corresponding with the flattened portion of said chuck head and with the roughened cylindrical portion thereof, respectively, said wheel having a pivotal pawl action on its eccentric pivot when said roughened portions engage, and a fixed non-rotative position when the flattened portions engage; and means for holding said wheel in service relation to said flattened and roughened portions when so disposed.

6. A tool handle having a grip portion; a chuck head adapted to receive a working tool, said chuck head having a flattened portion and a cylindrical engaging roughened portion, said roughened portion and flat portion being adjacently disposed; a mutilated wheel eccentrically and slidably mounted on said grip portion adjacent said flattened and roughened chuck head portion, said wheel having a flattened portion and a roughened periphery corresponding with and adapted to engage the flattened portion of said chuck head and the roughened cylindrical portion thereof, respectively, said wheel having a pivotal pawl action on its eccentric pivot when said roughened portions engage, and a fixed non-rotative position when the flattened portions engage; and means for holding said wheel in service relation to said flattened and roughened portions when so disposed, said means embodying a spring-seated plunger yieldingly mounted on said handle grip, and a plurality of finder sockets disposed on said wheel with reference to the operating positions thereof.

JOHN PEYER.
